UNITED STATES PATENT OFFICE

PATRICK ALPHONSUS MARTIN, OF BIRMINGHAM, ENGLAND

Application filed November 21, 1930, Serial No. 497,274, and in Great Britain June 7, 1930.

This invention relates to spring belts, braces, garters, sock suspenders, bands and the like of the type comprising a spring band formed from wire bent from side to side in a zig-zag fashion with loop coils at the bends of the wire, suitable connecting or attachment parts or other fittings being secured to the band.

The object of the present invention is to provide an improved and more efficient method of securing the connecting or attachment parts or other fittings to the spring bands whereby such parts may be more readily attached and whereby greater security is obtained.

According to the invention the fittings are provided with bent-back, folded-over or loop or hook parts the closed or returned transverse ends of which have oppositely-directed edge portions engaged laterally between longitudinally adjacent coils of the band.

Figure 1 of the accompanying drawing is a front elevation of a spring waist-belt constructed according to the present invention.

Figure 2 is a view on a larger scale showing the spring band in elevation and the leather fittings or attachments in section.

Figure 3 is a longitudinal section through the belt.

Figure 4 is a view showing the clip for securing the two springs, in front elevation and upon a larger scale than is shown in Figure 2.

Figure 5 is a similar view but showing the rear side of the clip.

Figure 6 is a section on line 6-6, Figure 5.

Figure 7 is a rear elevation of the belt.

Figures 8 and 8a show the leather fittings in their initial flat form before being attached to the spring band and folded over.

Figure 9 shows a modified method of securing the ends of the two springs together, the leather buckle-carrying fitting being shown in section.

Figure 10 is a rear elevation of a belt showing a modified method of attaching it to the band.

Figure 11 shows the leather buckle-carrying fitting of this modification, partly in sec-

Figure 12 is a cross-section on line 12-12, Figure 10.

Figure 13 is a longitudinal section on line 13-13, Figure 11.

Figure 14 shows the spring band and the buckle fitting of this modification before being attached.

Figure 15 is a rear view illustrating another modification.

Figure 16 is a cross-section on line 16-16, Figure 15.

Figure 17 shows the leather buckle-carrying fitting or strap partly in section.

Figure 18 represents the said buckle-carrying fitting or strap in its initial flat form before being attached.

Figure 19 is a rear view showing another method of attaching a leather end fitting to the folded

end of the belt, the leather end fitting being attached to the belt in such a manner that the leather end fitting may be sewn to the belt.

Figure 20 shows in elevation a side elevation of the invention as applied to braces.

Figure 21 is a sectional view, on a larger scale, showing how one of the end fittings is secured to the shoulder bands.

Figure 22 is a side elevation of the braces to the same scale as Figure 24.

Figure 23 is a cross-section on line 26-26, Figure 24.

In carrying out the invention in connection with a spring waist belt as shown in Figures 1 to 8 of the drawings, the spring band forming the main part of the belt is, in the example shown, composed of three longitudinal sections A, B, C. The section A is connected at opposite ends respectively to a leather strap or tab 1 carrying the buckle 2 and to a leather tab or fitting 3 engaging a ring 4 which may carry a hook 5. The section B is connected at opposite ends to a leather tab or fitting 6 on the said ring 4 and to another similar leather tab or fitting 7 engaging a ring 8 carrying a hook 9; and

an end fitting provided with a returned part having oppositely-directed edge portions engaged laterally between longitudinally adjacent coils of the spring band, and a metal clip device for securing together the end parts of the side-by-side springs, said clip device having tongues passed through coils of both the springs and bent over.

3. In belts, braces, garters, sock suspenders and other bands, the combination with a spring band comprising two side-by-side component springs each formed from wire bent from side to side with loop coils at the bends, of an end fitting comprising a main part lying over one face of an end of the band, and a folded part of less width having its opposite edges engaged between longitudinally adjacent coils along the inner edges of the respective component springs, and means for securing said component springs together on both sides of the folded part of the end fitting.

4. In belts, braces, garters, sock suspenders, and other bands, the combination with a spring band consisting of two side-by-side springs each formed from wire with loop coils at opposite sides, of an end fitting consisting of a flexible strap having a main part lying over the face of one end of the band, a part of reduced width intermediate the ends and a folded-back extremity folded about the reduced part and secured to the main part to form a loop enclosing the end of the band, the opposite edges of said reduced part being engaged laterally between longitudinally adjacent coils on the inner edges of the respective springs, and means for securing together the ends of the said two springs within the loop.

40 5. In belts, braces, garters, sock suspenders, and other bands, the combination with a spring band formed from wire with longitudinal rows of loop coils, of an end fitting of flexible material having a body portion and an end portion turned over and secured to the body portion to form a loop, the bight of said loop having a plurality of edge portions engaged between adjacent coils of different longitudinal rows of the band, a pair of the coils within the loop engaging the bight of the loop.

65 6. In belts, braces, garters, sock suspenders, and other bands, the combination with a spring band formed from wire with loop coils at opposite edges, of a flexible fitting having a body portion and an end portion turned over and secured to the body portion to form a loop, said loop having an aperture in the bight thereof through which the end of the spring band is passed so that the parts of the loop on opposite sides of the aperture engage between longitudinally adjacent coils of the spring band.

7. In belts, braces, garters, sock suspenders, and other bands, the combination with a

spring band consisting of two side-by-side springs each formed from wire with longitudinal rows of loop coils at opposite sides, of an end fitting having a main part lying over the face of one end of the band, an intermediate portion, and a folded-back extremity folded about the intermediate portion, said intermediate portion having edge portions engaged between adjacent coils of the longitudinal rows of the respective springs.

8. In belts, braces, garters, sock suspenders, and other bands, the combination with a spring band consisting of two side-by-side springs each formed from wire bent from side to side with loop coils at the bends, of an end fitting made of flexible material having a main part lying over the face of one end of the band, a folded over part secured to the main part of the band to form a loop enclosing the end of the band, the folded portion being engaged laterally between longitudinally adjacent coils of the band and having an aperture, and a longitudinal lacing cord joining together the adjacent edges of the two springs of the band, the said lacing cord being passed into the loop through the aperture in the folded part of the fitting.
